ALOIS HABLA, OF RADING-THEUSING, NEAR KARLSBAD, CZECHOSLOVAKIA

BRICK KILN FOR BURNING OF BRICKS AND SIMILAR ARTICLES

Application filed July 30, 1928, Serial No. 296,368, and in Czechoslovakia July 29, 1927.

The invention consists of a brick kiln for burning of bricks and similar articles. This kiln consists of two long walls covered with plates, thus forming a burning space, open at the ends, burning taking place to and fro. In this burning space there are erected division walls of unburnt bricks thus forming burning chambers. These division walls have numerous openings and do not stretch the whole width of the kiln. They are so arranged alternately that if one end of one of these is against one wall, then the end of the next one is against the other wall, so that one part of the hot gases passes sinuously through the kiln and another part of hot gases passes through the faces of the division walls into the next chamber. According to the way in which these division walls are erected more or less hot gases can pass through openings through these walls. Further, there is placed over the whole cross section, i. e. width, of the kiln, in front of the division walls, a partition wall of movable iron or burnable material. On removing or burning this partition wall connection is obtained with the next chamber. By using various methods of setting these division walls one can seal the chamber more or less well without the use of partition walls. On removing of the partition wall one part of the hot gases will pass through the set kiln in sinuous form, and therefore pass through the chambers in parallel; while another part of these gases passes through numerous openings formed in the division walls which are made of unburnt bricks, when the partition wall is either removed or burned, into the next chamber.

The long walls, built permanently of brick-work, contain smoke channels and heat conducting channels. Otherwise the operation is similar to that of a continuous kiln. Heat from the cooling chambers can be withdrawn and in the usual manner utilized for water-smoking and pre-drying.

Mainly the emptying of the kiln takes place from the ends; the centre chambers may be emptied by a door built in the centre of the long walls. The procedure can also be carried out in more than one burning space formed by more than two walls near to each other,

open at the ends and provided with temporary division walls. When using more long walls to form further burning spaces, next to each other, one of these spaces can be used as a drying chamber. In the attached drawings (Figs. 1-8) are shown brick kilns for carrying out this procedure in various ways.

Figs. 1, 2, 3, 4 show a simple kiln for small operations.

Fig. 1 shows a cross section of the kiln.

Fig. 2 is an elevation of the kiln.

Fig. 3 is a plan.

Fig. 4 shows a fully set kiln in plan with the division walls.

Fig. 4a shows a cross section through the firing.

Fig. 5 shows a plan of a double kiln.

Fig. 6 shows a cross section of a double kiln.

Fig. 7 shows a triple kiln in plan.

Fig. 8 is an end-elevation of the kiln, shown in Fig. 7.

Figs. 9, 9a, 9b show the temporary division walls with respect to the partition walls in vertical cross section.

Figs. 10 and 11 show a part of a set kiln in longitudinal section with various methods of setting the division walls.

Fig. 12 shows the centre wall of a double kiln.

Fig. 13 shows the removable or burnable (partition) walls in plan.

Fig. 14 shows the covering plates of the kiln.

The kiln, shown in Figs. 1-4 consists of two parallel walls M_1 and M_2 , and which, as is shown in Fig. 2, are covered by a roof. The two permanent walls M_1 and M_2 contain the smoke flues R_1 and R_2 , which are connected by branch flues e with the burning space, and these branch channels can be closed by dampers G . Both the smoke flues R_1 and R_2 are connected to a chimney or a ventilator (fan or blower) and connected to each other by a cross channel h . Above the smoke flues are arranged the heat conducting channels W_1 and W_2 , which are provided with openings u , which can be uncovered to take the heat conducting tubes (not shown) from any particular portion of the set kiln.

Fig. 4 shows the kiln set with goods to be

- burnt in chambers 1—10. The division walls of each of the burning chambers 1—10 are built of bricks to be burnt. In the Figs. 9, 9a, 9b, 10 and 11 the division walls *a* are shown in vertical cross section, they do not stretch the width of the kiln, instead they leave passage ways *b* at the ends as shown in Fig. 4. In order to prevent a rush of air, during the burning, there is introduced, between the individual division walls a partition wall *c* (see Figs. 4 and 13) made of iron, or similar, or else of a burnable material; should these be made of burnable material, then the burning takes place as with the paper partitions of a continuous kiln. In order to prevent a sudden rush of air through the top of the kiln, the movable wall *c* is provided with an iron gutter *d*, which can be filled with isolating material, sand or such. This affects the sealing at the top of the kiln as shown in Figs. 9, 9a, 9b and 10. The covers can also be constructed in a similar way to the covers in a continuous kiln, without arches, see Figs. 10 and 11. On the right of Fig. 10 is shown the sealing of the division wall on top by gutters *d* and *e*; on the left is represented the division wall after removing the partition wall *c*. The kiln is covered with plates (Fig. 14). The procedure with the above described kiln is carried out in the following manner: The kiln is partly or fully set with goods to be burnt, and a small smoke fire is lit at the firing place *f*, this is strengthened in the usual way until it can be increased to the main fire. By the opening and closing of the smoke dampers *G*₁ and *G*₂ and others the fire is conducted as in a continuous kiln. By removing or burning of the partition wall *c* there will eventually follow a connection with the succeeding chamber. Should one wish, for example, to conduct the fire from chamber 2 to chamber 3, then the partition wall *c* is removed, and if this consists of a burnable substance then the removal automatically takes place by the fire. The removal or burning of the partition wall covering the passage way left by the division wall must take place before the removal or burning of the part of the partition wall lying against the division wall itself, in order to allow the hot gases to pass into the succeeding chamber. In this way the draught is parallel with the particular division wall until eventually the particular partition wall is destroyed. On moving the partition wall *c* then the hot gases will take the way indicated by the arrows *p*. A small part of the hot gases will pass through the numerous openings of the division wall, made of unburnt bricks, and so will burn these bricks. Besides this, as shown by various arrows on Fig. 4 the streaming of the hot gases through the division walls is no longer parallel, instead enclose an angle,

according to the method of setting as shown in Fig. 11.

As usually 2—4 chambers are in fire, according to the size of the kiln, it will be enough if there is a movable or burnable partition wall *c* only behind every second or third division wall *a*, made of unburnt bricks. In the circumstances where chambers 5 and 6, Fig. 4, are in full fire, one can use the heat of chambers 1—2 to predry or finally dry the bricks in the freshly set chambers. This takes place by means of conducting tubes connected to the heating flues *W*₁ and *W*₂, and the particular chambers that are cooling. It is arranged that slightly warm air is used for pre-drying and warmer air for after drying.

As soon as chambers 1—3 are cold the bricks can be carted out, this occurs from the ends after the temporary end walls are removed. The setting of the chambers can therefore immediately proceed again. In order to make use of the heat of chambers 7—10 it is necessary to empty chambers 4—6 through a side door *g*. When chambers 1—4 are again set with fresh bricks then the heat of the last chamber can be used for pre- and after drying of these bricks. When the heat of the last chambers has been used up for the fresh setting in the first chambers, then the carting out of the bricks by lorries or railway wagons, from chamber 10 to 6 or 7 can begin from the ends. Chambers 10 and 11 are in full fire and chambers 12—14 are being smoked.

The kilns shown in Figs. 5 and 6 and also 7 and 8 are designed for large outputs. The procedure for operating is similar to the kiln described above. When chambers 18, 19, 20 (Fig. 5) are not yet set, though ready for setting, and chambers 1—3 ready to be emptied, chambers 4, 5, 6 and 7 cooling, chambers 8 and 9 in after fire, chambers 10, 11, 12 and 13 in full fire and chambers 14—15 in pre-firing, while 16—17 are water-smoking, burnt ware can be removed from chamber 1—7 with wagons from the end of the kiln. Thereupon, commencing from chamber 7 the chambers up to 1 can be reset with goods to be burnt. The emptying of chambers 7, 8, 9 and also 5 and 6 as well as 14, 15 and 16 can take place from side doors *g*. The removal of the goods by means of the side doors *g* may be dispensed with, as the burning space is long enough. It is not of great matter, if 25—30% of the space is left free for the purpose of carting out and in.

In the case of the triple kiln, as shown in Figs. 7 and 8, with 35 chambers, the burning space can also be used as drying space. With such a kiln the centre compartment is most usefully used as a drying chamber, in order to conduct the heat by the shortest way to the individual drying chambers. The continuance of the fire from chamber 12 to cham-

ber 35 is brought about in this case by means of the connecting flue F respectively from chamber 24 to chamber 1 by means of channel F₁. There is shown in Fig. 12 a centre wall of a double or multi-fold kiln. There are two heat-conducting flues W, and a smoke removing flue R which is provided with branches e reaching to either side. The smoke, as also the heat, can always be removed by the shortest way by means of these channels. The loss of radiant and conducted heat is therefore considerably less than in an ordinary continuous kiln, despite this one is always in the position to bring the heat in the shortest way to the individual burning chambers for pre- and final drying. There is a further advantage in that the drying process can always be conducted with two or more conducting channels. Further one is in the position, by the forming of a long burning space, to burn with much draught, and so attain a great fire-progress and a great kiln capacity. In order to quickly change over the cover plates from a covered to an uncovered chamber a crane can be used, if necessary. The troublesome and time wasting carting in and out of the bricks, or such like, with hand carts, can be dispensed with in these kilns, as carts, railway wagons, lorries and such like can be directly driven into the kiln. There is indicated in Figs. 7 and 8, railway lines or track lines, which are covered during burning with isolating material; by the provision of these considerable manual labour is saved, which together with the saving in initial cost and saving in fuel has an important influence on the general economy of these kilns.

I claim:

- 40 1. A brick kiln comprising long, spaced and substantially parallel walls, division walls of unburnt open brick work extending partly across the space alternately from the long walls to form a sinuous passage from end to end of the kiln, means to supply gases to the kiln, a portion of said gases passing through the sinuous passage and another portion passing directly through the division walls.
- 50 2. A brick kiln comprising spaced, substantially parallel long walls, having smoke removing flues and heating flues therein, means connecting the smoke flues of the walls together, partition walls of unburnt open brick-work extending alternately from one long wall toward the other to form sinuously arranged chambers, means connecting the smoke flues with said chambers, and means in the heat conducting flues for the attachment of pipes.
- 60 3. A brick kiln comprising long, spaced, and substantially parallel walls, division walls of unburnt open-brick work extending partly across the space alternately from the long walls to form a sinuous passage from

end to end of the kiln, means to supply gases to the kiln, a portion of said gases passing through the sinuous passage and another portion passing directly through the division walls, and removable partitions operable in conjunction with one or more division walls and extending entirely across the space between the long walls. 70

4. A brick kiln comprising long, spaced, and substantially parallel walls, division walls of unburnt open brick-work extending partly across the space alternately from the long walls to form a sinuous passage from end to end of the kiln, means to supply gases to the kiln, a portion of said gases passing through the sinuous passage and another portion passing directly through the division walls, and combustible partitions co-operating with said division walls. 75

5. A brick kiln comprising long, spaced, and substantially parallel walls, division walls of unburnt open brick-work extending partly across the space alternately from the long walls to form a sinuous passage from end to end of the kiln, means to supply gases to the kiln, a portion of said gases passing through the sinuous passage and another portion passing directly through the division walls, and combustible partitions partly within the division walls and extending from 90
one long wall to the other. 95

6. A brick kiln comprising long, spaced and substantially parallel walls, division walls of unburnt open brick-work extending partly across the space alternately from the long walls to form a sinuous passage from end to end of the kiln, means to supply gases to the kiln, a portion of said gases passing through the sinuous passage and another portion passing directly through the division walls, removable covers for the kiln chambers, removable partitions associated with one or more chambers, a gutter at the top of the partitions outside the kiln, a cap engaging partly on the top of the kiln, and a sealing medium sealing the meeting edges of the cap and gutter and kiln top. 100

In testimony that I claim the foregoing as my invention, I have signed my name hereto. 110

ALOIS HABLA.
